(57) CLAIM

The ornamental design of a battery terminal, substantially as shown and described.

DESCRIPTION

FIG. 1 is a perspective view showing the front, top and left side design of the battery terminal;

FIG. 2 is a top plan view of the FIG. 1 terminal;

FIG. 3 is a right side elevation view of the FIG. 1 terminal, and, FIG. 1 shows a left side view of the FIG. 1 terminal;

FIG. 4 is a front elevation view of the FIG. 1 terminal;

FIG. 5 is a rear elevation view of the FIG. 1 terminal; and,

FIG. 6 is a bottom plan view of the FIG. 1 terminal. The broken lines in FIGS. 5 and 6 are included for the purpose of illustrating portions of the terminal that form no part of the claimed design.
